UNITED STATES PATENT OFFICE.

JULIUS J. DRAWE AND WALTER J. TURNBULL, OF NEW ORLEANS, LOUISIANA.

PACKAGE-TIE

No. 892,948.

Specification of Letters Patent.

Patented July 7, 1908.

Application filed July 29, 1907. Serial No. 386,058.

To all whom it may concern:

Be it known that we, JULIUS J. DRAWE and WALTER J. TURNBULL, citizens of the United States, residing at New Orleans, in the parish of Orleans and State of Louisiana, have invented certain new and useful Improvements in Package-Ties; and we do hereby declare the following to be a full, clear, and exact description of the invention, such 10 as will enable others skilled in the art to which it appertains to make and use the same.

Our invention relates to improvements in package ties, and it has for its object to provide a tie of this character which shall be simple and inexpensive to manufacture, and which shall enable the package to be quickly tied and untied at will, and which when tied will form a perfect lock knot which cannot 20 slip or work loose.

With these and other objects in view, our invention comprises the novel features of construction and combination of parts more fully described hereinafter and particularly 25 pointed out in the claims.

Referring to the accompanying drawings forming a part of this specification, Figure 1 represents our tie in place upon a package with the string applied thereto and formed in 30 a finished knot. Fig. 2 represents the same tie on an enlarged scale showing with greater particularity the construction into which the wire forming our tie, is bent. Fig. 3 represents a modified form of our tie which may be 35 struck out of a single piece of sheet metal. Fig. 4 represents another modified form of our tie made out of a single piece of wire; as applied to a package and Fig. 5 represents a further modification.

Referring to the accompanying drawings forming a part of this specification, A represents the body of our tie which is preferably made from a single piece of wire and provided with the eye or loop B and the arms C 40 and D. The arm C is formed by bending the body A to form the bulge E and the apex F, and then over into the curve or crown portion G as shown in Fig. 2. The arm D is then formed by continuing the bending of 45 the wire from the crown portion G over on the other side of the body A up to the bulge or point H and the apex J, and then over until the looped end K is brought back to the wire, all as shown in Fig. 2. These bulges E 50 and H approach nearer to the body A than do the other portions of the arms, and thereby

aid in forming a sort of pocket as shown, into which the cord fits, especially if it is a large one, and they also thereby serve to prevent the loops of the cord from working out, when 60 the contents of the package are removed and the cord loosened. In this procedure a space L is also left between the lower portion of the body A and the crown G, as shown in the drawings, for a purpose hereinafter more 65 fully disclosed. In the modified form shown in Fig. 3 the parts A', B', C', D' and L' are all similar to the corresponding parts just described and perform precisely the same functions, but the said parts are struck out of a 70 single piece of sheet metal. As is well known to those skilled in the art of metal working, a large number of such ties can be manufactured by a single stroke of a suitable die.

In the modification shown in Fig. 4, the 75 structure is precisely the same as that shown in Fig. 2 except the eye or loop B is replaced by the modified form of loop M, which is formed by bending the body portion A over itself to form the eye M' and the stock portion M² as shown. This form has the 80 important advantage of permitting one end of the string or cord N to be fastened in the eye portion M' and a bight of the said string N to be slipped over the stock portion M² 85 into the eye portion M' and then quickly passed around the package as shown in Fig. 4. It will be seen that this constitutes an important advantage and also an important 90 feature of our invention.

The modified form shown in Fig. 5, is 95 precisely like the form disclosed in connection with Fig. 2, except both ends are made alike and provided with the arms C and D. In this form we are enabled to form 100 a lock tie knot at one end as shown at Fig. 4 and to also form the same knot at the other end. We may also slip a bight of the cord, likewise shown in Fig. 4, over one of the 105 arms of flukes C or D.

In operation, all the operator has to do is to securely fasten in any manner he chooses one end of the cord to one end of our tie, to then pass the cord or string around the package in any manner he chooses and then 110 secure the other end of the cord either by jamming the same into the space L or L' of our tie, or by otherwise fastening it. But in practice it will be found quicker and more convenient to pass the cord over the arm portion C of our tie, let it slip down to the crown portion G then across the lower

end of the tie and over the arm D, and let it slip down into the locking space L when a secure locking tie knot is formed. The whole operation is capable of being done 5 with much greater ease and in less time than it takes to tell it; and should the contents of the package become less and the tension of the cord thereby loosened the loops of the cord will still be held in place by the bulges 10 E and H above described.

It will thus be seen that our device is exceedingly simple and certain in operation, and is very cheap to construct. In fact the form disclosed in Fig. 3 with an ordinary 15 cutting die can be made almost at the cost of the metal it contains, for the reason that it may be made out of scrap material, and the other forms with suitable machinery for bending the wire can be made out of 20 wire with a cost slightly exceeding the price of the wire. It therefore follows that the cost of this tie is trifling and that it can be easily thrown away by department stores, 25 post-offices and other users without a material loss to themselves.

Having now described our invention, what we claim and desire to secure by Letters Patent is:—

1. A package tie composed of a single piece 30 of metal and provided with a body part; means at one end of the same to which may be secured the end of a cord or string and a pair of arms at the other end extending towards the opposite end of the body part 35 and provided with apex portions, and the bulges E and H, said arms being connected by a crown portion, and a space being left between said crown portion and the extreme lower end of said body portion into which 40 the said cord may be jammed, substantially as described.

2. A package tie composed of a single piece of wire having a body part; means at each end of said body part for securing a 45 cord or string thereto; one of said securing means on one end comprising a pair of arms

extending towards the opposite end of the body part and having bulge portions E and H, approaching said body part more closely than other portions of said arms; said wire 50 also having a crown portion G, joining said arms, and leaving a space between the same and the said body part into which a cord may be securely jammed, substantially as described. 55

3. A package tie composed of a single piece of wire and provided with a body part; a means at one end for securing a cord thereto, and a pair of arms at the other end extending towards said first mentioned end and joined by a crown portion, there being a space between the said portion and the lower end of said body portion into which the said cord may be jammed, substantially as described. 60

4. A package tie composed of a single piece of wire having a body portion; a loop at one end to which the end of a cord may be fastened and a pair of arms at the other end of said body extending towards the first 70 mentioned end and each arm provided with a bulge portion and an apex portion and joined by a crown portion, there being a space between the said crown portion and the lower end of said body portion into which 75 the said cord may be jammed, substantially as described.

5. A package tie composed of a single piece of wire having a body portion, and a pair of arms at each end joined by crown portions, 80 there being spaces between the said crown portions and the ends of the body portion, into which a cord may be jammed, substantially as described.

In testimony whereof, we affix our signatures, in presence of two witnesses. 85
